IGNITION DEVICE

Louis H. Segall, Sidney, N. Y., assignor to Bendix
 Aviation Corporation, New York, N. Y., a corporation of Delaware

Application September 27, 1947, Serial No. 776,600

8 Claims. (Cl. 315—57)

1

This invention relates to ignition apparatus and more particularly to a combined spark plug and transformer coil unit adapted for use in the ignition system of an internal combustion engine.

One of the objects of the present invention is to provide a novel radio shielded spark plug and transformer coil unit which is simple in construction, durable, and reliable in operation.

Another object is to provide a unit of the above character having a relatively small number of parts.

Another object is to provide novel simplified means for mounting a transformer coil in a shielded spark plug.

Still another object is to provide a shielded spark plug having a transformer coil which, through the provision of novel mounting means therefor, is held in its proper position by friction, thus materially simplifying construction and assembling of the various parts of the spark plug and decreasing manufacturing cost thereof.

A further object is to provide a shielded spark plug and transformer coil unit having an expandable conducting element which operates to hold the coil in proper position in the spark plug and to connect the high voltage or secondary winding of said coil with the center electrode of said spark plug.

A still further object is to incorporate a transformer coil in a shielded spark plug in a novel manner whereby said coil is supported by the center electrode assembly and is completely enclosed in an insulating compound so as to seal the same against moisture and to substantially eliminate or minimize danger of flashovers.

These and other objects and novel features of the invention will more fully appear from the following detailed description when the same is read in connection with the accompanying drawing. It is to be expressly understood, however, that the drawing is for the purpose of illustration only and is not intended to define the limits of the invention, reference for this latter purpose being had primarily to the appended claims.

In the drawing, the single figure is a longitudinal sectional view of one form of spark plug embodying the present invention.

The single embodiment of the invention illustrated in the drawing, by way of example, includes a radio shielded spark plug of the type now in common use on aircraft and similar engines. In the form shown, the spark plug comprises a tubular metallic shell 10 which is externally threaded at 11 for cooperation with a

2

threaded opening in an engine cylinder (not shown), and is provided with an upwardly extending metallic shielding barrel 12 which may be integral with or otherwise suitably secured to said shell. For purposes to hereinafter appear, the inner diameter of barrel 12 is larger than the inner diameter of shell 10, and the bore 13 extending through said shell is provided with a tapered wall portion 14.

Secured to the lower end of shell 10, as by silver solder or any other suitable means, is a ground electrode 15 which may be of any suitable known construction and cooperates in spark gap relation with the exposed lower end of a center electrode 16 that is mounted in the bore of a ceramic or the like insulator 17 for conducting high tension electrical current therethrough. Center electrode 16 is electrically connected to a terminal plug 18 which is disposed at the upper end of insulator 17 and extends into the bore of said insulator.

The center electrode assembly comprising electrode 16, insulator 17, and plug 18 is preferably mounted in shell 10 in such a manner as to prevent any gas leakage between said insulator and said shell. This mounting is effected by wedging a sleeve 19 of relatively soft metal, such as copper, between a surface of insulator 17 and the tapered wall 14 in shell 10. The sleeve engaging surface of insulator 17 may be coated with a thin layer of powdered graphite, a soldering flux or the like, and may also be provided with a slight taper.

A transformer coil is slidably mounted in barrel 12 in a novel manner whereby the mounting of said coil in said barrel and the electrical connections therefor with a supply lead and with the center electrode 16, 18 are materially simplified without affecting the efficiency of the spark plug. In the form shown, the transformer coil comprises a tubular core 20 of magnetic metal. This core preferably consists of a few turns or layers of sheet metal, such as silicon iron, forming a laminated tube which surrounds and extends above the upper end of insulator 17 in the annular space between the latter and barrel 12. In order to guard against flashovers of high tension current, the upper and lower ends of core 20 are spaced a safe distance from grounded parts of the spark plug. The outer surface of the metal of said core is coated with a thin film of suitable electrical insulation, such as enamel, to reduce eddy current losses to a minimum.

One or more layers 21 of insulating material are wound around core 20 and a secondary coil

winding 22 is then applied thereto, the several layers of said coil winding being separated in a well-known manner by layers of insulating sheet material 23. A primary winding 24, which may consist of a single layer, is wound around the last insulated layer of the secondary winding 22 and is, in turn, surrounded by a two-ply insulating layer 25. Surrounding insulating layer 25 is a split sleeve 26 of magnetic metal, such as silicon iron, which acts as a path for magnetic flux in conjunction with core 20.

It is to be noted that the several layers of primary and secondary coil windings 24, 22 do not extend longitudinally beyond the length of core 20, and that the initial or first layer of the secondary winding is space wound to accommodate the high frequency potential and to prevent flashovers between the turns thereof. Additionally, the insulating layers 21, 23, 25 extend an appreciable distance beyond the opposite ends of primary and secondary windings 24, 22 and are spaced inwardly from the opposite ends of barrel 12 to further shield said windings from grounded parts of the spark plug. In a commercial embodiment, the primary and secondary coil windings 24, 22 consist of 25 turns and 2000 turns, respectively, of "Formvar" No. 25 and No. 42, respectively, heat resisting enamel covered copper wire, and the insulating layers 21, 23 and 25 are made of a polytetrafluoro-ethylene material known as "Teflon" which is a plastic film having good heat resistance and dielectric properties. In the interest of clarity, all of the insulating layers are shown as single lines in the drawing.

The high potential end of secondary winding 22 is connected, such as by a thin strip conductor 27, to the core 20 which, in turn, is connected to the terminal plug 18 of the center electrode assembly by means of an expandable conductor element in the form of an open wound tension coil spring 28 made of a suitable electrically conductive material, such as stainless steel. Normally, the outside diameter of conductor spring 28 is slightly larger than the inside diameter of core 20 so that when said spring is placed within said core it will by its expanding action in a radial direction engage the uncoated inner surface of the core with sufficient pressure to not only make good electrical contact therewith but to hold the coil assembly tightly and support the same on the center electrode assembly in proper position lengthwise of barrel 12. Conductor strip 27 is disposed between the insulating layers 21, 23 and extends through the layer 21 and is thus kept clear of the grounded parts of the spark plug.

Projecting into the upper end of coil unit 22, 24 and fitting tightly in the bore formed by the inner insulating layer 21 is a tapered plug 29 of ceramic or other insulating material. This latter plug is provided with a straight lower portion 30 of reduced diameter which extends loosely into the bore of core 20 and forms an external annular shoulder 31 which engages the upper end of said core. The length of plug 29 is so chosen that when the shoulder 31 thereof is engaged with core 20 as above described, the conductor spring 28 will be properly positioned thereby between the ends of said core, whereupon the coil unit 22, 24, through engagement of said spring with the terminal plug 18 of the center electrode assembly, will be supported by said assembly in proper position lengthwise of barrel 12 and provide a space above and below the same as indicated at S, S, for receiving a filling compound, as hereinafter de-

scribed, to prevent flashovers from the inner high tension windings.

The end of the outer or low potential layer of the secondary winding 22 is connected to the adjacent end of the primary winding 24 as indicated at 32, and both said ends are connected to one end of a common thin conducting strip 33, the opposite end of which is connected, as by means of silver solder, to an input terminal 34. The connection 32 is made between the plies of the outer insulating layer 25, and the conducting strip 33 extends upwardly therefrom between said plies into the upper space S in barrel 12 and across the upper end of plug 29. Conducting strip 33 is made of good electrically conducting material, such as pure nickel. The opposite or other end of primary winding 24 is connected to ground by connecting it to the barrel 12 as at 35 through a thin conducting strip 36 which is similar to the conducting strip 33 and extends upwardly between the plies of the outer insulating layer 25.

The input terminal 34 is in the form of a pin made of high grade steel and is fixed in a glass seal 37 which is molded or cemented in a flanged tubular member 38 which extends into the upper end of barrel 12 and serves to hold the coil assembly in place in said barrel. Input terminal 34 projects beyond the lower surface of member 38 to have the conducting strip 33 connected thereto, and when said member is inserted in barrel 12 the end of said strip is pushed into a cavity 39 formed in plug 29 to take up the slack. One or more thin washers 40 of insulating material are engaged over the lower end of terminal 34 before conducting strip 33 is connected thereto in order to insulate said strip from the grounded member 38. In the final assembly, the flange of member 38 is engaged with the upper end of barrel 12 and said member is secured to said barrel by a series of overlapping spot welds which provide a press fit and insure a moisture tight seal. The outer end of member 38 is externally threaded for receiving a shielding conduit for an incoming supply lead (not shown) which may be of standard size and known construction.

After member 38 is secured in place, the spaces S, S within barrel 12, the cavity 39, and the spaces around and inside the coil unit are filled with a suitable insulating compound 41, such as for example, a compound commercially known as "Styrene base Q 447," manufactured by Dow Chemical Company. For this purpose, the shell 10 is provided with a port 42 which opens outwardly through the side of said shell and communicates with the lower space S in barrel 12. Before filling the spark plug with the insulating compound 41, the entire assembly is placed in an oven for approximately 6 to 8 hours at about 150° Fahrenheit for precautionary drying out of the same. The spark plug is then placed in a tank and evacuated at 25 to 28 inches vacuum after which the insulating compound 41 is forced into the spark plug through the port 42 under atmospheric pressure for approximately five minutes to insure filling of the spaces S, S, the cavity 39, and all the void spaces around and inside the coil assembly. If desired, pressure above atmospheric pressure may be employed for introducing the filling compound into barrel 12. The port 42 is then closed by a taper pin plug 43 to retain the liquid compound in the barrel 12, said plug being driven into said port and thereby exerting additional pressure on the filling compound. The filled spark plug is then allowed to stand for a time interval to permit setting of the

filling compound to a solid mass of a resilient non-moldable material, but this setting may be accelerated by baking said plug for approximately fifteen hour at 140° Fahrenheit or four hours at 200° Fahrenheit. The compound 41 contracts about ten percent in setting and provides a good seal around the inner circumference of the spark plug to guard against flashovers from the high tension windings, and because of the hermetic sealing of barrel 12, said compound will withstand the high temperatures with which the spark plug is subjected under operating conditions. For the sake of clarity, the filling compound 41 is not shown in the spaces around the coil assembly.

There is thus provided a novel combined radio shielded spark plug and transformer coil unit which is simple in construction, has relatively few parts, and wherein the mounting of the transformer coil and the electrical connections therefor with a supply lead and with a center electrode is materially simplified through the provision of novel mounting means. Additionally, the novel construction and arrangement of the transformer coil and mounting means therefor substantially eliminates or reduces to a minimum the danger of flashovers within such a unit.

Although only a single embodiment of the invention is illustrated and described, it is to be expressly understood that the same is not limited thereto. The transformer coil and mounting means therefor may be embodied in spark plugs of other constructions, such as those having mica insulation instead of ceramic. Various other changes may also be made, particularly in the design and arrangement of parts illustrated and in the materials mentioned without departing from the spirit and scope of the invention as will now be clear to those skilled in the art. For a definition of the limits of the invention, reference is had primarily to the appended claims.

What is claimed is:

1. In apparatus of the class described, a tubular metallic shell, an insulated center electrode assembly mounted in said shell and projecting therefrom, a metallic shielding barrel extending from said shell around and beyond the projecting end of said assembly, an ignition coil slidably mounted in said barrel and comprising primary and secondary windings, a tubular metallic core for said coil surrounding the outer end of said assembly, means for connecting the high potential end of said secondary winding to said core, and means disposed within said core for mechanically supporting said coil on the outer end of said assembly and for electrically connecting said core with the electrode of said assembly, said last-named means comprising a radially-expansive open-wound coil spring arranged with its axis parallel with the axis of said core and engaging the electrode of said assembly and the inner surface of said core under radial tension.

2. In apparatus of the class described, a tubular metallic shell, an insulated center electrode assembly mounted in said shell and projecting therefrom, a metallic shielding barrel extending from said shell around and beyond the projecting end of said assembly, an ignition coil slidably mounted in said barrel and comprising a tubular metallic core surrounding the outer end of said assembly, an open wound coil spring disposed within said core and engaged with the latter under radial tension and with the outer end of said assembly for supporting said coil on said assembly in pre-determined position with respect to the longitudinal axis of said barrel, and a ta-

pered plug of insulating material tightly fitted in and carried by said coil for properly positioning said spring axially with respect to said core.

3. A combined spark plug and coil unit comprising a tubular body member, an insulated electrode assembly mounted in said member and projecting upwardly therefrom, a shielding tube extending from said member around and beyond the outer end of said assembly, an ignition coil slidably mounted in said tube and surrounding the outer end of said assembly, said coil comprising a tubular metallic core and primary and secondary windings thereon, means for electrically connecting said secondary winding with said core, a radially-expansive open-wound coil spring disposed within said core and having portions thereof engaged with said core and with said assembly, said spring operating to electrically connect said core to the electrode of said assembly and exerting radial pressure against the inner wall of said core to mechanically support said coil on said assembly so that the opposite ends of the coil are spaced inwardly from opposite ends of said tube, a plug of insulating material tightly fitted in said coil for positioning said spring axially with respect to said core, a metallic closure member for closing the open end of said tube and spaced from said coil, an elongated terminal in said closure member and insulated therefrom, said terminal projecting into the space in said tube above said coil, means for electrically connecting said primary winding to said terminal, and insulating means filling the spaces in said tube above and below said coil.
4. An ignition unit comprising a tubular core of magnetic metal, primary and secondary windings on said core, said secondary winding and core being electrically connected, and a radially-expansive open-wound coil spring of electrically conductive material disposed within said core and engaging the inner surface thereof under radial tension.
5. An ignition unit comprising a tubular core of magnetic metal, primary and secondary windings on said core, said secondary winding and core being electrically connected, a radially-expansive open-wound coil spring of electrically conductive material disposed within said core and engaging the inner surface thereof under radial tension, and an insulating plug extending into and engaging the end of said core and positioning said spring axially with respect thereto.
6. An ignition unit comprising a tubular core of magnetic metal, a secondary winding on said core, a primary winding on said secondary winding, insulating sheets between adjacent layers of said windings and between the inner layer of said secondary winding and said core, said insulating sheets extending beyond said layers and said core and said secondary winding being electrically connected to said core, a radially-expansive open-wound coil spring disposed within said core with its axis parallel with the axis of said core and engaging the inner surface thereof under radial tension, and an insulating plug in one end of said insulating sheets and projecting into and engaging the end of said core for positioning said spring axially with respect to said core.
7. In apparatus of the class described, a coil comprising a tubular metallic core and a plural layer winding thereon having sheet insulating material between and extending axially beyond the layers thereof, and an insulating plug having a tight fit in said projecting insulating material,

said plug having an annular shoulder engaging the end of said core.

8. In apparatus of the class described, a metallic barrel, an insulated electrode projecting into said barrel, a coil having sheet insulation between and extending axially beyond the layers of the coil winding, and means for positioning said coil around one end of said insulated electrode intermediate the ends of said barrel comprising an insulating block having a tight fit in said projecting sheet insulation and a radially expandable conductor engaging the internal wall of said coil under tension and interposed between said electrode and said block.
